UNITED STATES PATENT OFFICE.

PETER J. JOECKEN, OF CLEVELAND, OHIO, ASSIGNOR TO THE AMERICAN WASHBOARD COMPANY, OF SAME PLACE.

WASHBOARD.

SPECIFICATION forming part of Letters Patent No. 556,541, dated March 17, 1896.

Application filed February 26, 1895. Serial No. 539,737. (No model.)

To all whom it may concern:

Be it known that I, PETER J. JOECKEN, a citizen of the United States, residing at Cleveland, in the county of Cuyahoga and State of Ohio, have invented or discovered certain new and useful Improvements in Washboards, of which improvements the following is a specification.

The invention described herein relates to certain improvements in washboards wherein provision is made by means of a movable protector for the formation, in connection with the brand-board, of a soap box or receptacle in such relation to the rubbing face or faces that the soap will be protected, as well as the clothes of the operator.

In general terms the invention consists in the construction and combination substantially as hereinafter more fully described and claimed.

In the accompanying drawings, forming a part of this specification, Figure 1 is a view in side elevation of a washboard having my improvement applied thereto. Fig. 2 is a sectional elevation of the same. Fig. 3 is a view similar to Fig. 2, showing a modification in the lock for the protector. Figs. 4 and 5 are sectional elevations showing the application of the improvement to double-faced washboards. Fig. 6 is a view similar to Fig. 4, showing the protectors provided with side pieces, and Fig. 7 is a perspective view of the folding protectors, showing the construction of the trunnions at the ends thereof.

The washboard is formed as usual, consisting of the head-piece 1, cross-bar 2, side bars 3, rubbing-face 4, and brand-board 5. The protector 6 is provided at its inner corners with trunnions adapted to fit in suitable sockets formed in the side bars and located at such a distance from the head-piece as will permit of the protector being folded up against the brand-board and when adjusted to position for protector use will form, in connection with the brand-board, a soap box or receptacle. The protector is held in operative position to form the soap-box and perform its function as a protector by means of a spring 7 attached to the frame of the board in such manner that its free end will

bear upon the protector when turned down and prevent its being turned up, and can be pressed inwardly, so as to allow the protector to be folded up against the brand-board for transportation and storage. The protector 55 is prevented from turning down sufficiently far to allow the escape of the soap from the receptacle by the bearing of the rear end of the protector against the brand-board, the trunnions being located a short distance from 60 the rear edge of the protector.

In lieu of the means described for holding the protector in operative position a groove 8 may be formed in one of the side bars in such position that when the protector is 65 turned down to operative position it can be moved longitudinally, so that one of its edges will engage said groove and be held thereby until moved longitudinally in the opposite direction.

In the construction shown in Fig. 4, showing the application of my improvement to a double-faced washboard, two independently-movable protectors 9 and 10 are employed. These protectors are provided with trunnions 75 fitting within suitable sockets in the side bars, and are so arranged in relation to each other that their rear edges will bear one against the other when one of the protectors, as 9, is adjusted to position for protector use, and the other protector, 10, is folded up against the brand-board, so that the folded protector 10 will serve as a stop to prevent the protector 9 from dropping down beyond operative position. This construction will permit of both 85 protectors being folded up against the brand-board, one on each side thereof, but when one of the protectors is shifted to operative position the other protector cannot be shifted to corresponding position on its side of the wash- 90 board without at the same time causing the first protector to turn up against the brand-board.

The construction shown in Fig. 5 is a modification of Fig. 4 and one in which one of the 95 protectors will serve as a brand-board while the other is in position for protector use. In this construction the protector which is folded up will serve as a lock for the other protector, preventing its being turned down far enough 100

to permit the soap to drop out, and the protector which is in operative position will prevent, by reason of its rear edge bearing against the lower edge of the folded protector 5 below its pivotal point, the latter from being turned down to operative position until the first protector has been folded up. In this construction, wherein one protector operates as a brand-board, a stop 11 is attached to the 10 under side of the head-piece to prevent the protectors when being folded up from passing entirely through the brand-board space.

If desired, the protectors may be formed with V-shaped end pieces 12, so as to entirely 15 inclose the soap, as shown in Fig. 6, in which case the protectors will not fold flat against the brand-board, but will move inwardly sufficiently to permit of the soap-receptacle being protected by another washboard when 20 packed for transportation.

I claim herein as my invention—

1. The combination, with a washboard, of a protector pivotally mounted in side bars at such a distance below the head-piece as to 25 form, in conjunction with the brand-board, a receptacle for the soap above the protector, and to be capable of being folded into the brand-board space, and a stop formed by the brand-board for holding the protector above

the rubbing-face in position for use, substantially as set forth. 30

2. The combination, with a double-faced washboard, of two pivotally-mounted protectors arranged to form a receptacle for soap in connection with the brand-board, when 35 shifted to position of use above the rubbing-faces, said protectors being arranged in such relation to each other that one protector will be held in operative position by the other protector, substantially as set forth. 40

3. The combination in a double-faced washboard, of two pivotally-mounted protectors arranged to be adjusted to position for protector use above the rubbing-faces, and, when so adjusted, to form, in connection with the 45 brand-board, a soap box or receptacle, and to be folded into the brand-board space, said protectors being so arranged with relation to each other, as to lock each other, the one in operative position and the other in its folded 50 position, substantially as set forth.

In testimony whereof I have hereunto set my hand.

PETER J. JOECKEN.
